DESIGN FOR AN ELECTRIC HEATER

Jason B. Swartzbaugh, Toledo, Ohio, assignor to
The Swartzbaugh Manufacturing Company,
Toledo, Ohio, a corporation of Ohio

Application November 2, 1945, Serial No. 123,409

Term of patent 7 years

(Cl. D81—10)

To all whom it may concern:

Be it known that I, Jason B. Swartzbaugh, a citizen of the United States and resident of Ottawa Hills, Toledo, in the county of Lucas, and State of Ohio, have invented a new, original, and ornamental Design for an Electric Heater, of which the following is a specification, reference being had to the accompanying drawing, forming a part thereof.

In the drawing, Fig. 1 is a front perspective

view of an electric heater showing my new design and Fig. 2 is a side perspective view thereof.

The dominant features of the design are shown in full lines. Both sides of the electric heater are substantially the same in appearance.

I claim:

The ornamental design for an electric heater, substantially as shown and described.

JASON B. SWARTZBAUGH.
